Application April 19, 1930, Serial No. 445,548

65 Claims. (Cl. 200—162)

This invention relates to electric switches and while it is of general application, it is particularly applicable to disconnect switches.

In the design of disconnect switches of very high current carrying capacity certain problems arise which do not arise in the design of switches of lower current ratings. For instance, other things being equal, the heating of a switch is proportional to the square of the current carried thereby and increases directly with the electrical resistance of the switch. The electrical resistance is a function of the temperature and increases as the temperature increases. Thus any increase in the current carried by the switch would of itself result in a heating of the switch, which heating would result in an increase in the switch resistance, thus causing further heating. At the point of engagement between the switch blade and the switch contact there is bound to be a certain amount of electrical resistance. The greater the current flow the more heat there will be developed at that contact; hence the problem of reducing the contact resistance and of increasing the rate of heat radiation becomes of great importance as the current rating of the switch increases. Disconnect switches are infrequently operated, hence the blade and the contact may both become coated with oxide or other impurities while the switch is open. Upon closure of the switch this must be scraped away since such impurities are of comparatively high resistance.

It is one of the objects of the present invention to provide a switch wherein there is a cleaning action as the switch is closed and wherein contact resistance is reduced and heat radiation is greatly facilitated.

I have invented a switch which operates on the principle of making contact between the movable blade and the stationary clips at a relatively large number of points, each having a comparatively small area, instead of making contact through one or two flat surfaces of a relatively large area as in the conventional type of switch.

In one embodiment of my invention the contact clip comprises a large number of wires which are simultaneously engaged by the blade. The wires are preferably arranged in two rows, although the invention is not limited to such an arrangement since a greater or a lesser number of rows may be used if desired. Each wire is fastened at one end and is located in the path of movement of the switch blade so that the blade slides over the wire, the wire being maintained in firm contact with the blade by its own resiliency. The opposite end of each wire is prefer-

ably permitted a limited amount of motion and normally lies in the path of movement of the blade. As the blade is moved to the closed position it forces the free end of the contact wire out of its path, the blade sliding along the contact wires. This sliding action takes place over a comparatively small area and there is a considerable pressure between the sliding parts, with the result that the sliding is accompanied by a scraping or cleaning action which removes all oxide and other foreign matter. The contacting surfaces are thus always clean and the contact resistance is reduced to a minimum. The contacting portion of the switch blade is preferably made convex to further decrease the contacting area and thereby increase the unit pressure at the contact.

In another embodiment of my invention the blade consists of a large number of laminations spaced from one another to facilitate heat radiation and arranged to make contact by a wiping motion crosswise of the laminations whereby impurities that may be present are scraped away and clean contacting surfaces are presented.

It is a further object of the present invention to provide an improved switch lock for locking the switch against opening due to the forces that may be present during extremely heavy current flow, such as may take place during short circuiting conditions. The blade consists of two parallel blade members secured together in spaced relationship by means of spacing pins or the like. A latch is mounted on the stationary structure for engaging one of the blade spacing pins to lock the switch against being blown open by excessive current flow. The blade is provided with a pivoted pull ring which has a cam portion that engages the latch upon the initiation of the switch opening motion and it moves the latch to the released position. The latch and pull ring are of a very simple design and may be used for either single throw or double throw switches. The eye of the pull ring is shaped so as to allow a prong or switch stick to be inserted therein and initially apply its pull as far as possible above the center of the blade when actuating the switch to the open position.

A further object of the invention is to provide a high pressure multiple switch contact comprising spring contact elements that are under initial tension, that is, prestressed.

By placing the contact fingers, such as the wire members or similar spring members under initial tension by lateral displacement, and holding them from expanding to their unstressed

position, it is possible to secure a high spring pressure with a very small amount of displacement. The effect of closing the switch is merely that of transferring the spring pressure from the stop to the blade or arm contact. As the spring contacts require only minute displacement to make the transfer of pressure, the switch is closed easily and without danger of stabbing the contact fingers.

10 Since the resistance of a contact decreases with increase of unit pressure of the engaging surfaces, the practical advantage of gaining high unit contact pressure with small lateral displacement is obvious. This is particularly important in switches where a rigid switch contact and a multiple spring contact are brought into engagement in the relation of an arm or tongue thrust between gripping jaws, or vice versa.

15 The attainment of the above and further objects of the present invention will be apparent from the following specification taken in conjunction with the accompanying drawings showing a few proposed embodiments thereof.

In the drawings:—

20 Figure 1 is a top plan view of a switch constructed in accordance with my invention;

Figure 2 is a side elevation thereof;

Figure 3 is a sectional view taken along the line 3—3 of Figure 5;

25 Figure 4 is a view similar to Figure 3 showing the position of the clip when the switch is open;

Figure 5 is a fragmentary sectional view of the contact clip and latch mechanism when the switch is closed;

30 Figure 6 is a fragmentary top view of one of the contact clips prior to the insertion therein of the contact wires;

Figure 7 is a section taken along the line 7—7 of Figure 2 and looking in the direction of the arrows;

35 Figure 8 is a view similar to Figure 4 showing a somewhat modified form of contact clip;

Figure 9 is a side view of the hinged portion of a somewhat modified form of switch;

40 Figure 10 is a top plan view of another form of the switch constructed in accordance with my invention;

Figure 11 is a side elevational view of the switch shown in Figure 10;

45 Figure 12 is a section taken along the line 12—12 of Figure 11;

Figure 13 is a sectional view taken along the line 13—13 of Figure 11;

Figure 14 is a sectional view taken along the line 14—14 of Figure 12;

50 Figure 15 is a top plan view of another switch constructed in accordance with my invention;

Figure 16 is a side elevational view of the switch shown in Figure 15;

55 Figure 16a is a view of one of the laminations constituting the switch blade;

Figure 17 is a sectional view of the hinge contact of the switch of Figure 16, said view being taken along the line 17—17 of Figure 16;

60 Figure 18 is a view taken along the line 18—18 of Figure 16, looking in the direction of the arrows;

Figure 19 is a sectional view taken along the line 19—19 of Figure 16 and looking in the direction of the arrows; and

65 Figure 20 is a fragmentary sectional view taken along the line 20—20 of Figure 15.

Reference may now be had more particularly to the form of switch shown in Figures 1 and 2.

70 This switch comprises a supporting base 1 which

is preferably, although not necessarily, of metal and is grounded as indicated at 2. A pair of insulators 3 and 4 are mounted upon the base 1 for supporting the live switch parts. The insulators 3 and 4 may be of any standard construction and they are secured to the base in a manner well known in the art. A hinge clip frame 5 is secured to the top of the insulator stack 3 and provides a support for a line terminal 6, a contact clip 7, and a duplex switch blade 8. The switch blade 8 comprises two blade members 11 and 12 which are of similar construction and which are secured together in spaced relationship by means of blade spacers 18 and 19. The hinge clip frame 5 is provided with two upstanding arms 10—10 on the outside of which the blade members 11—12 are hinged by means of a hinge pin 13 and nuts 14. As shown, the blade straddles the contact clip 7, the two blade members lying upon the opposite sides of the clip. The clip 7 is of a construction substantially similar to the construction of the clip 25 which is engaged by the free end of the blade and which will be fully described as the description proceeds.

25 At the end of the blade remote from the hinge I mount a pair of lock bearing plates 30 and 31. The plate 30 is mounted on the inner side of the blade member 11 and the plate 31 is mounted on the inner side of the blade member 12. A pull ring 32 is pivoted between the lock bearing plates by means of a hinge pin 33 which extends through the blade members 11 and 12, through the bearing plates 30 and 31, and through the pull ring 32. Suitable nuts 34 and 35 are threaded on the opposite ends of the hinge pin 33 for securing the various parts together. The hinge pin 33 together with the nuts 34 and 35 secure the free ends of the blades together and prevent outward spreading of the blades. Spacer pins 27 and 28 35 extend between the lock bearing plates 30 and 31 and serve to maintain those plates suitably spaced apart and therefore to maintain the spacing between the blade members 11 and 12. The blade members receive the contact clip 25 between the pins 19 and the pins 27—28 and maintain a firm engagement with the contact clip.

40 The blade engaging clip 25 is part of a contact terminal 40 which is mounted upon the insulator 4. The terminal 40 is provided with a line terminal 41 for receiving a line and with the clip 25 for establishing connections with the switch blade. In addition a latch or pawl member 45 is mounted on the contact clip frame. The pawl 45 is pivoted on the clip frame by means 45 of a pin 46 and is biased to the locking position by means of a pair of springs 47—47. An extension 48, formed on the latch, limits the extent of turning of the latch in a counter-clockwise direction as seen in Figure 5 by abutting against the clip frame. The hook portion of the latch is adapted to engage the top of the pin 28 and to thus lock the blade against outward movement by any magnetic forces that may be developed due to the current flowing through the switch. During the switch closing movement the pin 28 rides on the tapered portion 49 of the latch, thus forcing it to turn slightly to the right as seen in Figure 5 to permit the full closing of the switch. When the switch reaches the full closed position the springs 47 turn the latch to the position shown in Figure 5, thus locking the switch blade in position. The pull ring is provided with a cam portion 50 which is adapted to force the latch or pawl 45 from its locking position to the 50

unlocked position upon the initial pulling upon the ring to open the switch. More will be said of this as the description proceeds.

An explanation will now be given of the construction of the contacting portion of the contact clip. The clip comprises a pair of arms 51 and 52 extending from the base of the contact clip frame in spaced relationship and secured together at opposite ends by means of a bridging portion 53 formed integrally with both of said arms. Between these two walls and on opposite sides of the center of the contact clip are mounted two rows of spring contact wires, said two rows being indicated at 55 and 56, respectively. A row of holes is drilled through the base of the contact clip frame between the arms 51 and 52 and on one side of the center of the frame as indicated at 57 and a similar row of holes is drilled on the other side of the center of the contact clip frame as indicated at 58. These holes are drilled at a slight angle to the vertical, preferably about 4° 15' although this angle may be greatly varied without departing from the spirit of the present invention. Wires of hard copper or other suitable spring conducting material are inserted through the respective drilled holes in the rows 57 and 58. The rows of wires are indicated at 55 and 56, respectively. After both rows of wires have been pressed into the holes and properly aligned they are secured in place and in good electrical contact with the base by peening the metal of the base around the wires at the points 57' and 58'. Each wire has a loop portion or eye formed therein as indicated at 59 and when the wires are initially inserted into the drilled holes they assume a position such as is indicated in dotted lines of Figure 4 due to the fact that the drilled holes are at an angle to the vertical. In the assembly of the contact clip the wires of the row 55 are pressed inward toward the center at their free end and a pin 60 is passed through holes in the walls 51 and 52 of the contact clip and through the loops of the respective wires of the row 55, thus retaining these wires in the position shown in full lines in Figure 4 in a prestressed condition. They are held in this position under spring tension due to the resilience of the material of which they are made. In a like manner the row of wires 56 is retained in the inward position by means of a pin 61 which is inserted into position in the same manner as is the pin 60. Washers are strung on the pins 60 and 61 between the contact wires to prevent the contact wires from being sprung sideways when the blade is being closed. When the contact wires are in this position it is to be noted that they extend transversely beyond the edge of the walls 51 and 52 of the switch clip. There are a number of practical advantages in placing these wire fingers 55-56 under initial tension or prestress. First, by bending these spring fingers, such as 55 or 56, from the dotted line position in Figure 4 to the full line position there shown, a certain prestress or inherent stress due to the deflection is provided. In other words, when the blades 11-12 come down over the wires 55-56, the blades need to displace the spring fingers only enough to force the loops 59 free of contact with the back sides of the pins 60 and 61, and the pressure is as great as though the blade had actually forced the springs from the dotted line position shown in Figure 4 to the full line position shown in Figure 3.

In practice, this means that the blades engage the ends of the spring fingers at a very low angle, and closing of the blade is surprisingly easy. The amount of effort or work required to close the switch is less with the prestressed contacts than is required where the blades must displace the spring contact to gain the necessary stress required.

In addition, the switch with prestressed contacts is more compact and economical of material than prior switches. Also, in the case of a row of contacts, such as 55 or 56, the contacts of each row are held in accurate alignment by the common restraint of the pin 60 in case of the row of springs 55 and the pin 61, in case of the row of springs 56.

Any desired degree of prestressing (within the limits of the design) may be provided by changing the angle at which the holes are directed.

It is to be noted that the upper portion of the side walls 51 and 52 are tapered or curved inwardly as indicated at 65 and 66, said tapered portions merging with the bridge portion 53. This tapered nose portion serves as a guide for guiding the switch blade as it is moved into the full closed position. The switch blade members 11 and 12 are in general flat but the contacting portion of the blade, that is, the portion of the blade that engages the contact wires, is made convex as indicated at 67 and 68. When the switch blade is moved to the closed position it forces the rows of contact wires 55 and 56 inward from the full line position shown in Figure 4 to the full line position as shown in Figure 3. The contact wires exert an outward pressure against the inner surfaces of the duplex blade and each wire is free to make a contact with and exert its pressure against the surface of the blade entirely independent of the action of any of the other contact wires. It will be further noted that when the blade is in its closed position the contact wires are approximately perpendicular to the base and that the portions of the blade members which are opposite the contact wire present a very small contact area to them due to the convex surface of the blade at the contacting portion. This arrangement insures contact being made at the center of the blade, thus using the material of the blade efficiently for both electrical conductivity and heat radiation. The use of many wires in parallel to carry current from the switch blade to the clip base also uses the electrical conductivity of material efficiently and permits free circulation of air around the clip and the blade. The engagement of the convex surface of the blade, such as 12, crosswise with the cylindrical wire, such as 56, is geometrically a point only. In practice, it is an exceedingly small area with very high unit pressure. The combination of contact wires of circular cross section and a convex surface on the blade produces a switch contact that is self-cleaning and not readily thrown out of alignment. During the closing motion of the blade the convex surface of the blade rests against the contacting portion of each of the spring contact wires in the respective rows of wires with a considerable pressure at the point of contact due to the fact that the area of contact with each wire is very slight. This rubbing action serves to scrape clean the contacting point of the blade as well as the contacting points of the wires, thus eliminating the resistance that would otherwise be present due to the formation of a coat of oxide or other impurities.

A reenforcing web 70 of a substantially inverted channel-shaped cross section extends between the walls 51 and 52 of the clip, being formed integrally therewith. In addition the wall 52 of the clip has a slot formed therein as indicated at 71 for permitting the locking latch 45 to swing about its pivot to the right as seen in Figure 5.

The contact 7 is of a construction substantially identical to the contact 25 previously described, differing therefrom in that since no latch such as the latch 45 is provided adjacent this contact clip it is not necessary to provide the wall corresponding to the wall 52 with an opening wherein that latch may swing. The switch blade members 11 and 12 are convex at 75 and 76 adjacent the contact clip 7 in the same manner as adjacent the contact clip 25. As a result of the provision of the contact clip 7 the hinge 13 of the blade is not required to carry current. It is also to be noted that a rather wide surface is provided between the switch blade members and the arms 10 to which the blade members are hinged, thereby rendering it difficult for the blade to be forced out of alignment.

To open the switch a switch stick of a standard construction is used. The stick is provided at its end with a prong which is inserted into the eye of the pull ring 32 and a pull is exerted in a direction to open the switch. Since the switch is locked by the latch 45 against opening, the pull ring swings about the hinge pin 33 in a clockwise direction. The cam portion 50 bears against the tapered surface 49 of the latch 45 and forces the latch to move to the right as seen in Figures 2 and 5. Upon continued movement of the cam portion 50 the latch is released from engagement with the pin 28 so as to permit opening of the switch. The cam portion 50 moves into abutment with the pin 28 thereby preventing further turning of the pull ring about its pivot 33. Continued pulling on the pull ring 32 results in the swinging of the blade about its pivot to open the switch.

Reference may now be had more particularly to Figure 8 showing a somewhat modified form of contact clip for use in a switch such as is shown in Figure 1. This contact clip may be used adjacent the hinge or adjacent the free end of the blade. Instead of using separate wires in the opposite rows 55 and 56 as in the previous construction the opposite wires of the two rows are, in this construction, integral. Each one of the wires comprises a loop 80, the opposite ends of which are inserted into the openings 57 and 58 in the same manner as previously described. This includes the prestressing or placing of the spring wire loop 80 under initial stress. This prestressing is secured by drilling the holes in the base not vertical to the face, but at a slight angle to the vertical. Thus the holes at the right hand side of Figure 8 are drilled with the axis sloping outwardly away from the vertical to the right, and the holes on the left hand side are similarly drilled with their axes sloping outwardly away from the vertical toward the left. When the ends of the shanks 81, 82 are brought into registration with the corresponding drilled holes, they may be forced into the holes by endwise thrust. The inclination of the holes guides the extremities toward each other, producing a tendency to bulge the wires away from each other in the middle. This prestressing may be further accentuated by forming the loop initially with the sides or shanks diverging from each other, i. e., lying farther apart than the distance be-

tween the holes into which these ends are forced. This wire 80 is in general flexible and the two sides 81 and 82 thereof correspond to the two wires 55 and 56 of the switch previously described. It is to be understood that a large number of wires such as the wire 80 are used in this clip, one wire for each pair of holes 57 and 58 of Figure 6. The wires are spaced from one another by washers, as in the previous construction. The washers are held on a pin 84 that extends between the side walls 51-52 of the clip and around which the wires 80 are looped.

In Figure 9, I show a modified form of hinge clip for a switch of the kind previously described. The blade 8', which is of a construction substantially the same as the blade 8 of Figures 1 and 2, is hinged to the hinge clip frame by means of a hinge pin 85 which passes through the two blade members and through a pair of arms 86 on the hinge clip and is secured in place by means of a nut as indicated at 87 and a similar nut on the opposite side of the hinge clip frame. Rows of contact wires such as indicated at 55 or 56 of the switch previously described are located on the opposite sides of the arms 86, one row being indicated at 88 and 89. Two sets of rows of contact wires such as the rows 88 and 89 are likewise located for engagement with the opposite blade member of the duplex blade 8'. The hinge contact clip is provided with a stop 90 for limiting the extent of opening movement of the switch blade to a position at right angles to its full closed position. This form of hinge contact clip may be used for a double throw switch by merely omitting the stop 90 and providing two free contacts like that shown in Figure 5 on opposite sides of and in line with the hinge contact and each other.

Reference may now be had more particularly to the switch shown in Figures 10 and 11. This switch, as the previous switch, consists of a hinge terminal clip and a contact terminal clip mounted upon insulators 3 and 4 which are themselves supported upon a base 1 as previously described. A duplex switch blade 100, comprising blade members 101 and 102 secured together in spaced relation, is hinged by means of a pin 104 and is adapted to be swung into engagement with a terminal clip 105. The hinge contact 106 is shown in section in Figure 12, from which it may be seen that it is similar in a good many respects to the terminal clip previously described.

The hinge terminal 106 has a bottom portion 107 into which are secured two rows of spring wire contacts indicated at 108 and 109 respectively, those contacts being secured in place in the same manner as are the spring wire contacts of the clip previously described. These spring wire contacts are considerably shorter than the spring wires of the contact clips previously described, and are secured in place at their opposite ends by means of pins 110 and 111 which pass loosely through eyes formed in the wire, the eyes or loops in the wire being of an appreciably greater diameter than the diameter of the pins. The contact wires are spaced from one another by means of washers 115, thereby preventing the ends of the wires 108 and 109 from sliding along the pins 110 and 111 during the closing movement of the switch blade. The contact clip is further provided with a top portion 117 in which are mounted depending spring wires 118 and 119, said wires being arranged in the same manner as are the rows of wires 108 and 109. It is to be noted that the wires in the four rows 108, 109, 75

118 and 119 are mounted so as to be normally disposed at an angle to the vertical, the drilled holes in the contact clip and into which the wires extend being preferably at an angle of about 5 $4^{\circ} 15'$ to the vertical, although any other angle may be selected. The pins 110 and 111 are provided for the set of spring contact wires 109 and 110 and corresponding pins 120 and 121 are provided for the other set of the spring contact 10 wires. These pins hold the contact wires in a position inward towards the center of the contact clip as compared to the position that they would naturally assume, due to their mounting in the drilled holes in the contact clip casting, in the 15 absence of these pins. In this construction the switch blade members 101 and 102 may be made flat at their contacting portion with the springs.

The contact clip 105 with which the opposite end of the switch blade engages is of a construction substantially similar to the contact clip 106 above described, differing therefrom mainly in that the last mentioned contact clip is provided with a gradually upwardly and inwardly tapering guiding portion 125. The guiding portion 25 125 serves to guide the switch blade in position since it is tapered and enters into the space between the blade members 101 and 102. The terminal upon which the clip 105 is mounted is provided with a locking latch or pawl 45, and the 30 blade is provided with a pull ring 32, both being of a construction such as has been previously described. The latch and the pull ring are effective to control the locking and unlocking of the switch blades. In order to facilitate the guiding of the switch blade members into the switch closed position the ends of the blades at the points along their lengths where they engage the contact clips are beveled as indicated by the reference numerals 127-127.

40 The manner of operation of this switch is substantially similar to that of the previously described switch and a further explanation is not believed to be necessary at this point.

Reference may now be had to the switch shown 45 in Figures 15 and 16. This switch comprises a pair of insulators 3 and 4 supported in the manner shown in Figure 2. A hinge terminal 135 is mounted upon the insulator 3 by means of bolts 136. The hinge terminal includes a contact tongue 137 formed integrally therewith. A support comprising a pair of substantially rectangular arms 140-140 is provided, and it is to this support that the switch blade 145, comprising the blade members 146 and 147, is hinged. 50 The supports 140 are secured to the opposite sides of the hinge clip 135 by means of screws 141.

A description will now be given of the duplex blade 145. This blade comprises two blade members 146 and 147 of similar construction. Each 55 of these blade members comprises a channel 148 between the webs of which are located laminations 149 spaced apart by washers or the like. The laminations comprise thin strips of copper or the like of the general shape shown in Figure 16a. The channels 146 and 147 are secured together in spaced relationship about midway of their length by a pair of plate members 150 and 151 and a number of pins or rivets 152 which extend between the plate members and through 60 the flanges of the channels and also serve to secure the laminated strips 149 and the washers 155 to the channels. The rivets 152 prevent movement of the midpoints of the laminations within the channels. The laminations are 65 secured to the channels at the opposite ends there-

of by means of rivets 160 and 161. The rivets extend through the flanges of the channels and through washers that space the laminations from one another. Each of the laminations has a hole formed therein through which the rivet passes, 5 the hole being of an appreciably larger diameter than the diameter of the rivet as may be clearly seen in Figure 20, so that the end of each lamination has a certain limited freedom of motion with reference to the rivets 160 and 161. It is to be 10 noted that the edges of the laminations are considerably spaced from the web of the channel members 147 and 146 at the two ends of the switch blade members. As a result there is a certain amount of give in each lamination if a 15 force is applied thereto at the point indicated at 165 or 166, tending to force it toward the web 20 of the channel. This give is possible due to the fact that the holes in the laminations at the points where the rivets 160 and 161 are located are of a considerably larger diameter than the diameter of the rivets.

The channels 146 and 147 are hinged to the frame arm 140 by means of pins indicated at 25 168. The two channels 146 and 147 are secured 30 together at their opposite ends by means of the pull ring 170 which is provided with a pair of arms 172 and 173 which are secured to the outer sides of the channels 146 and 147 respectively. Thus the pull ring not only serves as a means 35 for opening and closing the switch but also as a means for securing the two channel members together in spaced relationship. Each of the arms 172 and 173 is provided with a downwardly extending tapered guiding portion 174, which 40 may be seen more clearly in Figure 19, for the purpose of facilitating the guiding of the switch blade on the two sides of the contact clip 178. The contact clip 178 is a part of the terminal 180 that is secured to the insulator 4. The terminal 45 on the insulator 4 and the terminal on the insulator 3 are each provided with lugs for receiving a line conductor in the same manner as are the terminals on the switches previously described. The distance between the extensions 165 of the laminations on the opposite blade members 146 and 147 when the switch is open is less than the thickness of the contact clip 178. The contact clip is tapered at its edge so as to 50 facilitate the guiding of the switch blade members into engagement with it and as the switch is closed the contact clip member causes a spreading of the laminations at the point 165. The laminations make contact with the clip and slide along the same. There is a considerable amount 55 of pressure between the laminations and the contact clip due to the fact that the laminations are being spread apart out of their normal position. As a result there is a considerable scraping or 60 cleaning action brought about by the movement of the blade members to the closed position. As a result the contacting surfaces that are in engagement with one another when the switch is closed are quite clean and excellent contact is established. The same action takes place at the 65 extensions 166 adjacent the hinge portion of the switch blade, hence at this point also there is bound to be good electrical contact with the terminal 137.

It is to be noted that each lamination makes 70 contact with the contact clip at a very small area so that the unit pressure at that area is relatively large. The spacing of the laminations from one another serves two main purposes. Should there be an appreciable amount of foreign 7

matter upon the edges of the laminations or upon the contact clip then, due to the spacing between the laminations, this foreign matter may be readily scraped away, thereby tending to maintain a clean contacting surface. The second main function is that of increasing the heat radiation properties of the switch blade.

In compliance with the requirements of the patent statutes I have herein shown and described a few preferred embodiments of my invention. It is, however, to be understood that the invention is not limited to the precise embodiments herein shown, the same being shown for illustrative purposes only.

15 What I consider new and desire to secure by Letters Patent is:—

1. A switch contact comprising a plurality of parallel rows of substantially parallel spaced wires, and a support for both ends of the wires, 20 one of said ends being permitted a limited amount of motion transversely of the rows.

2. An electric switch contact clip having a base portion, a pair of spaced arms extending therefrom, and a row of spring contacts held at one 25 end in said base and held at their other end between said arms.

3. An electric switch contact clip having a base portion, a pair of spaced arms extending therefrom, and a set of rows of spring contacts held 30 at one end in said base and held at their other end between said arms by means including a lost motion connection whereby the springs have a limited freedom of motion at their said other end.

4. A contact housing open at its sides, a plurality of spring contact wires extending lengthwise of each of the open sides and having a portion thereof extending beyond the open sides of the housing, and a switch blade including portions adapted to straddle the housing and simultaneously engage with the contact wires on each side 40 of the housing.

5. A contact housing open at its sides, a plurality of spring contact wires extending lengthwise of each of the open sides and having a portion thereof extending beyond the open sides of the housing, and a switch blade including portions adapted to straddle the housing and simultaneously engage with the contact wires on each side of the housing, said contact housing including means for guiding a switch blade into its closed positions straddling the housing.

6. A switch including a plurality of spaced parallel rows of spring contact wires, and a pair of mechanically and electrically connected switch 55 blade contact members slidable into and out of simultaneous engagement with the opposite sides of the two rows of contact wires.

7. A switch including a plurality of spaced parallel rows of spring contact wires, and a pair of mechanically and electrically connected switch blade contact members slidable into and out of simultaneous engagement with the opposite sides of the two rows of contact wires, the contacting portion of the blades being convex.

65 8. A switch including a plurality of spaced parallel rows of spring contact wires, and a pair of mechanically and electrically connected switch blade contact members slidable into and out of simultaneous engagement with the opposite sides 70 of the two rows of contact wires, the spring contact wires being bowed towards the blade members to present a point contact thereto.

9. A switch including a plurality of spaced parallel rows of spring contact wires, and a pair 75 of mechanically and electrically connected switch

blade contact members slidable into and out of simultaneous engagement with the opposite sides of the two rows of contact wires, the contacting portion of the blades being convex and the spring contact wires being bowed towards the blade members to present a point contact thereto.

10. An electric switch comprising a contact clip having a base portion and a pair of spaced arms extending therefrom, a set of rows of spring wire contacts held at one end in said base and held at 10 their other end between said arms by means including a lost motion connection whereby the springs have a limited freedom of motion at their said other end, a switch blade having cooperating contact portions adapted to straddle both sets of 15 rows of contacts, and guiding means for guiding the blade into engagement with the spring wire contacts.

11. An electric switch including a contact member and a blade member, said blade being mounted for sliding movement onto and along the contact member for establishing contact therewith, one of said members comprising a large number of narrow flexible pieces bowed adjacent one end 20 towards engagement with the other member and engaging said other member at their bowed portions, and a lost motion connection including pin means passing loosely through the flexible pieces at their ends adjacent their bowed portions and at right angles to their direction of flexure for 25 securing them together while permitting them a limited degree of relative movement at the pin.

12. A contact clip comprising a top and a bottom, a long narrow spring contact extending upward from the bottom of the clip towards the 35 top, and a second long narrow spring contact extending downward from the top towards the bottom, both of said contacts being electrically connected and constituting the contacting portions of the single contact clip.

40 13. A contact clip comprising a top and a bottom, a row of long narrow spring contacts extending upward from the bottom of the clip towards the top, and a second parallel row of long narrow spring contacts extending from the top 45 towards the bottom, all of said contacts in both rows being electrically connected and constituting the contacting portions of the single contact clip.

14. A switch including a contact clip comprising a top and a bottom, a long narrow spring contact extending from the bottom of the clip towards the top, a second long narrow spring contact extending downward from the top towards the bottom, both of said contacts being electrically connected and constituting the contacting portions of the single contact clip, and a switch blade movable in a direction extending lengthwise of the contacts and sliding along and lengthwise of the contacts into the closed position.

60 15. A switch including a contact clip comprising a top and a bottom, a row of long narrow spring contacts extending upward from the bottom of the clip towards the top, a second parallel row of long narrow spring contacts extending 65 from the top towards the bottom, all of said contacts in both rows being electrically connected and constituting the contacting portions of the single contact clip, and a switch blade movable in a direction extending lengthwise of the contacts and sliding along and lengthwise of the contacts into the closed position.

16. A switch including a contact clip comprising a top and a bottom, a row of long narrow spring contacts extending upward from the bot-

tom of the clip towards the top, a second parallel row of long narrow spring contacts extending from the top towards the bottom, all of said contacts in both rows being electrically connected and constituting the contacting portions of the single contact clip, and a switch blade movable in a direction extending lengthwise of the contacts and sliding along and lengthwise of the contacts into the closed position, said blade being convex at the portion thereof that engages the contacts.

17. A switch blade including a channel frame and a plurality of laminations held between the flanges of the channel and spaced from the web thereof.

18. A switch blade including a channel frame and a plurality of laminations extending substantially the full length of the frame held between the flanges of the channel, said laminations constituting the contacting portion of the blade.

19. A switch blade including a channel frame and a plurality of laminations held between the flanges of the channel and spaced from the web thereof, and a pivotal support for the channel frame.

20. A switch blade including a channel frame and a plurality of laminations held between the flanges of the channel and spaced from the web thereof, said laminations lying in spaced planes parallel to the flanges of the channel.

21. A switch blade including a channel frame and a plurality of laminations held between the flanges of the channel and spaced from the web thereof, said laminations lying in spaced planes parallel to the flanges of the channel and constituting the contacting portion of the blade.

22. A switch blade including a channel frame and a plurality of laminations held between the flanges of the channel and spaced from the web thereof, said laminations lying in spaced planes parallel to the flanges of the channel, and washers between the laminations.

23. A switch blade including a channel frame and a plurality of laminations held between the flanges of the channel and spaced from the web thereof, said laminations constituting the contacting portion of the blade, and washers between the laminations.

24. A switch blade including a channel frame and a plurality of laminations held between the flanges of the channel and spaced from the web thereof, and a pivotal support for the channel frame, said laminations being secured to the channel at points spaced from the pivotal support and being free of the channel adjacent the support.

25. A knife switch comprising a hinge contact, a switch blade member pivoted thereto, and a contact clip member adapted to be engaged by the blade member by a motion whereby the two members slide into one another, said two members sliding along and into one another upon continued movement of the blade member after it initially contacts with the other member, said blade member comprising a large number of relatively thin parallel laminations the contacting edges of which are in the plane of movement of the blade and engage with the contact clip member by a scraping movement edgewise of the laminations whereby portions of the clip are successively scraped by the successive laminae.

26. A knife switch comprising a hinge contact, a switch blade member pivoted thereto, a con-

tact clip member adapted to be engaged by the blade member by a motion whereby the two members slide into one another, said two members sliding along and into one another upon continued movement of the blade member after it initially contacts with the other member, said blade member comprising a large number of relatively thin parallel laminations, the contacting edges of which are in the plane of movement of the blade and engage with the contact clip member by a scraping movement edgewise of the laminations whereby portions of the clip are successively scraped by the successive laminae, and washers between said parallel contacting members for spacing them apart to permit the circulation of air between said parallel members.

27. A switch comprising a hinge contact, a switch arm member pivoted thereto, and a contact clip member adapted to be engaged by the arm member by a motion whereby the two members slide into one another, said two members sliding along and into one another upon continued movement of the arm member after it initially contacts with the other member, said clip member comprising a large number of relatively thin and narrow parallel spring contacting wires arranged in two spaced rows on opposite sides of the arms for simultaneous engagement by the arm member.

28. A switch comprising a hinge contact, a switch arm member pivoted thereto, a contact clip member adapted to be engaged by the arm member by a motion whereby the two members slide into one another, said two members sliding along and into one another upon continued movement of the arm member after it initially contacts with the other member, said clip member comprising a large number of relatively thin and narrow parallel spring contacting members arranged in two spaced rows and flexible towards and away from one another for simultaneous engagement by the arm member, and spacing means between the parallel spring contacting members of each row for spacing them apart to permit the circulation of air between them.

29. A switch contact comprising a mounting base having at least two parallel rows of wire receiving holes formed therein, parallel spring contact making wires having their ends inserted into said holes and tightly held therein, the opposite ends of the wires having a limited freedom of motion, and a pin extending parallel to said rows of holes, the opposite ends of said wires being loosely looped around said pin.

30. A switch contact comprising a mounting base having at least two parallel rows of wire receiving holes formed therein, parallel spring contact making wires having their ends inserted into said holes and tightly held therein, the opposite ends of the wires having a limited freedom of motion, a pin extending parallel to said rows of holes, the opposite ends of said wires being loosely looped around said pin, and means extending beyond said looped ends of the wires for guiding a blade into wiping contact making engagement with the contact wires.

31. A switch comprising a plate-like switch contact, a metallic base member, and a row of wire springs disposed in parallel planes supported as cantilevers in said base, each of said springs having a surface of double convexity formed by bending of the wire whereby each wire is adapted to provide a substantially single point contact for engagement with said plate-like switch contact.

32. In a switch, a platelike contact member adapted to move in a predetermined plane, a cooperating contact device comprising a base extending approximately in a plane substantially transverse to the first plane, a row of spring rods supported as cantilevers extending in substantially parallel planes which are approximately normal to the first plane, said rods having surfaces of double curvature remote from the base defining contact points adapted to engage said plate-like contact member at substantially single points only, and means tending to hold said plate-like member in engagement with said double curved surfaces against the spring 15 of said rods.
33. In a contact making device, a blade having a surface generated by a moving line always parallel to a given line, a contact comprising a base, a row of spring rods mounted as cantilevers in said base, said rods being adapted to engage said surface, said engagements being confined substantially to single points by two degrees of curvature of the elements making up said engaging surfaces, at least one degree of curvature 25 appearing on the surfaces of said rods.
34. A multiple high pressure ventilated contact comprising a base member, a series of resilient rodlike elements mounted on said member for cantilever support thereupon, said elements having contact portions of double curvature, and intermediate spring portions between said base and said contact portions.
35. In combination, a stationary base plate, a blade member movable in a plane substantially normal to the base plate, a series of rodlike conductors disposed in a row, each conductor comprising an anchoring portion at one end by which it is fixed to and mounted on the base plate, a contacting portion at the other end for engaging the blade, and an intermediate resilient portion for allowing lateral movement of said contacting portion transversely of the row, said conductors being spaced apart for individual mechanical action and to promote ventilation, said contacting 40 portions being spaced from said base plate by said intermediate portions.
36. In combination, a base plate, a blade member movable in a plane substantially normal to the base plate, a series of aligned rodlike conductors, each conductor comprising an anchoring portion by which it is mounted on the base plate, a contacting portion for engaging the blade, and an intermediate resilient portion spacing the contacting portion from the base plate, said conductors being spaced apart for individual mechanical action and to promote ventilation, the engagement of each rodlike conductor with the blade being limited substantially to single point contact by virtue of the two engaging surfaces 45
- 60 possessing two degrees of convexity, said blade and said contacting portion having wiping engagement.
37. In combination, a blade movable in a definite plane, a cooperating contact comprising a base plate, a row of resilient rodlike conductors having anchoring portions disposed in a line parallel to said plane, said conductors having contacting portions adapted to engage said blade substantially at single points only with wiping engagement, said substantially single point engagements being produced by virtue of the shape of the engaging surfaces, which surfaces contain two degrees of convexity, said conductors having intermediate resilient portions between said anchoring portions and said contact portions ex-

tending substantially normally to the surface of the base plate to which they are anchored and serving to space them from each other.

38. In a switch, a rigid contact member, a yielding contact device cooperating with said member and comprising a plurality of double convex contact elements having separate rodlike stems and a rigid base to which said stems are rigidly anchored, said elements and said member having substantially single point contact, and the pressure of each element against the member being individually controlled by the corresponding rodlike stem, said rodlike stems serving as individual cooling means for the heat evolved by current flow through the corresponding contact, 15 said stems extending substantially normally to the surface of the base and serving to space the double convex contact elements from the base.

39. A contact making device comprising a rigid contact member having a contact surface, a 20 yielding contact member consisting of a rigid base, a series of wires disposed in a row with one end of each rigidly anchored for cantilever support of the outer end from the base and disposed out of contact with each other for individual 25 mechanical action and to promote cooling, said wires having transversely bent portions providing double curved contacting portions which are adapted to have each substantially a single point engagement with the contact surface, said double 30 curved portions being spaced from the base to permit resilient lateral deflection thereof.

40. A contact making device comprising a rigid contact member having a contact surface, a yielding contact member consisting of a rigid 35 base, a series of wires with one end of each rigidly anchored for cantilever support of the outer end from the base and disposed out of contact with each other for individual mechanical action and to promote cooling, said wires having transversely bent portions providing double curved contacting portions which are adapted to have each substantially a single point engagement with the contact surface, and means for holding said wires in prestressed condition.

41. In combination, a stationary contact device having contacting means facing in opposite directions, a movable contact device also having contacting means facing in opposite directions for engagement with the first means, said stationary contact device comprising a base, a series of spring fingers mounted for individual play and cooling, said spring fingers comprising rod-like elements of cross section presenting transverse convexity to the first of said contact means, said 55 spring fingers having bends providing convexity in a longitudinal direction whereby engagement of the spring fingers and the contacting means is substantially at single isolated points.

42. A switch contact member comprising a 60 substantially horizontal supporting base, a plurality of substantially vertically disposed spring wires of relatively small diameter having their lower ends fixedly secured to said base to provide a cantilever support, and having their upper 65 ends free to move laterally in making contact, and means to limit the play of the outer ends of said wires in making and breaking contact.

43. In combination, a U-shaped wire contact member having the ends of the limbs thereof rigidly connected, a cooperating contact member having two spaced contact surfaces facing each other, and means for forcing said two surfaces upon opposite sides of said U-shaped wire contact member.

44. In combination, a base member, U-shaped wire contact members the free ends of which are rigidly secured in said base member, a cooperating contact member having two spaced contact surfaces facing each other, and means tending to hold said surfaces in contact with said U-shaped members against the spring action of said U-shaped members.
45. A switch contact comprising a substantially horizontal supporting base, and a plurality of hairpin-shaped wire contacts arranged in substantially parallel rows and having their free ends fixedly secured to the base, and their outer ends curved to provide a point contact with a switch blade on either side and free to move laterally in making contact, and their intermediate portions constituting substantially straight line extensions of the secured ends and providing cantilever support for the outer ends.
46. A switch contact comprising a substantially horizontal supporting base, and a plurality of hairpin-shaped wire contacts arranged in substantially parallel rows and having their free ends fixedly secured to the base, and their outer ends curved to provide a point contact with a switch blade on either side and free to move laterally in making contact, and their intermediate portions constituting substantially straight line extensions of the secured ends and providing cantilever support for the outer ends, and means for protecting said hairpins from distortion beyond the limits of their resiliency on closing of the switch.
47. A switch contact comprising a substantially horizontal supporting base, and a plurality of hairpin-shaped wire contacts arranged in substantially parallel rows and having their free ends fixedly secured to the base, said wire contacts being adapted to be engaged upon opposite sides by a switch blade and being free to move laterally in making contact therewith, the intermediate portions of said contacts constituting substantially straight line extensions of the secured ends and providing cantilever support for the outer ends.
48. The combination of a contact device comprising a base member, and contact fingers comprising a row of parallel individual wires which have contact portions bent to the same form to provide free end portions with double curved surfaces, said wires having their opposite end portions substantially parallel to each other and extending in the same direction and being fixed in said base member, whereby the contact fingers constitute cantilevers for supporting pressure of a cooperating switch member upon said double curved surfaces, a cooperating switch member having a contact surface engaged along a substantially straight line by points on said double curved surfaces when the member and contact fingers are in engagement, and means for guiding said contact fingers and said switch member into wiping contact making engagement.
49. In a switch, a pair of relatively movable elements, the first element comprising a body having a continuous contact surface, the second element comprising a plurality of contactors having independent double curved surfaces presenting substantially point contacts lying in alignment, a rigid supporting member, resilient cantilevers fixed on said supporting member and carrying said contactors, said cantilevers being formed of wire, and means for guiding said elements into and out of wiping engagement with each other.
50. A switch contact comprising a rigid frame member, a spring wire contactor having a contacting portion and having one end anchored rigidly in said frame member, said wire contactor being deflected from normal unstressed position to stress the same, and means mounted on the frame back of said contacting portion for holding said wire contactor in said deflected and stressed position.
51. A switch comprising an arm guided for movement in substantially a predetermined plane, a contact member adapted to be engaged by the arm with a wiping motion when the arm is moved to switch closing position, said contact member comprising a base and a plurality of prestressed contact fingers having contacting portions adapted to be engaged by the arm.
52. In a switch, the combination of a first contact comprising a pair of spaced contact surfaces supported in fixed position relative to each other and a second contact comprising a rigid support, and contact fingers arranged in rows, said fingers being fixed at one end to said rigid support and extending in the same direction and having contact surfaces adjacent their outer ends coating with the contact surfaces on the first contact, the contact surfaces on one of said contacts being convex with respect to the other to reduce the area of actual engagement with the other, said contact surfaces of one contact facing away from each other and the contact surfaces of the other contact facing toward each other.
53. The combination of claim 52 wherein the fingers are resiliently stressed and means including lost motion connections for limiting the traverse of said contact fingers whereby they are maintained under said stress.
54. The combination of claim 52 wherein the relative movement of said contacts to open and close the switch is in a line substantially longitudinal of said contact fingers.
55. A switch comprising a pair of switch members between which there is relative movement for opening and closing a circuit, one of said members comprising spaced elements having contact surfaces facing toward each other, the other of said members comprising a rigid supporting element having a pair of prestressed flexible contact fingers extending therefrom, said fingers being rigidly anchored at one end and having high pressure contact surfaces of small area at their other ends, said high pressure contact surfaces facing in opposite directions, whereby they are adapted to engage the contact surfaces of the said one member.
56. The switch of claim 55 further characterized by lost motion means for limiting the separation of the fingers from each other.
57. In combination, a contact member comprising a pair of spaced contact surfaces held substantially rigidly in spaced relation to each other, a cooperating contact member comprising a rigid metallic supporting element having a plurality of spring fingers rigidly anchored to said supporting element at one end and having their other ends extending substantially parallel to each other, and lost motion means at the outer ends of the fingers for limiting the movement of the fingers with respect to each other, said fingers being urged resiliently against said lost motion means when the contact members are separated and being urged resiliently against said contact surfaces of said first member when said members are in engaging relation.

58. A switch comprising a relatively movable element and a relatively stationary element, the relatively stationary element comprising a rigid member having contact faces upon opposite sides 5 of a median plane, the relatively movable element comprising a movable frame member the median plane of which is adapted substantially to coincide with the median plane of the stationary element when the elements are brought into engagement, the frame member comprising a substantially rigid anchorage, a pair of rows of spring fingers fixed to said anchorage and having curved contact ends, the contact ends of said rows respectively engaging opposite faces of the 10 said rigid member, and a transverse bar for each row, each bar having lost motion connection with the spring fingers of the corresponding row.

59. In a switch comprising a metal mounting plate and insulators extending from said plate, 20 the combination of stationary contact members mounted on said insulators, one member comprising a base portion having a hinge element and adjacent thereto two rows of parallel wires anchored rigidly at one end and having their 25 outer ends disposed substantially in alignment, said wires being yieldable transversely of the respective rows, the other member comprising a base portion and adjacent thereto two rows of parallel wires anchored rigidly at one end and 30 having their outer ends disposed substantially in alignment, said wires being yieldable transversely of the respective rows, and a switch arm pivoted at one end upon said hinge element, said arm having substantially cylindrical contact surfaces engaging transversely of the wires of the 35 rows, respectively, at each end, whereby substantially point contact between the individual wires and the arm contact surfaces is secured.

60. The combination of claim 59, wherein the 40 hinge element of the first stationary contact is disposed at one end of the corresponding row of wires and wherein the second stationary contact has a locking element at one end of the corresponding row of wires and the switch arm carries a cooperating locking element and an eye member for operating the switch arm and for releasing the locking elements.

61. The combination of claim 59 wherein the 45 outer ends of the wires are bent into curves adapted to engage the transverse cylindrical contact surfaces of the arm when the arm and the wires engage, whereby stubbing is prevented.

62. A switch comprising a base, two parallel 50 rows of wire contacts rigidly anchored to the base, the individual wires being yieldable transversely of their rows, respectively, and a cooperating switch member comprising cylindrical surfaces each cooperating with a row, the longitudinal axis of each cylindrical surface being transverse with respect to the longitudinal axes of the 55 contact portions of the wires, whereby two sets of high pressure multipoint contacts are secured.

63. In a switch a relatively rigid contact member, and a relatively yielding multiple contact member, said multiple contact member compris-

ing a rigid metal base, a plurality of flexible wires having mounting ends rigidly fastened into the base for mechanical anchorage and for the conduction of current thereto, said first contact member being movable endwise along the length 5 of the wires to slidably engage a lateral surface of the same, said wires having portions adjacent their outer ends bent to provide limited engagement of each wire with the cooperating surface of the relatively rigid contact member, said wires 10 providing multiple limited area high pressure contact engagement with said rigid contact member, said wires adjacent their points of engagement with the rigid contact member being provided with means for limiting the deflection of 15 said wires in the direction of engagement with said first member whereby said wires are held in prestressed condition before engagement with the first member.

64. In a switch a relatively rigid contact member, and a relatively yielding multiple contact member, said multiple contact member comprising a rigid metal base, a plurality of flexible wires having mounting ends rigidly fastened into the base for mechanical anchorage and for the conduction of current thereto, said first contact member being movable endwise along the length 20 of the wires to slidably engage a lateral surface of the same, said wires having portions adjacent their outer ends bent to provide limited engagement of each wire with the cooperating surface of the relatively rigid contact member, said wires 25 providing multiple limited area high pressure contact engagement with said rigid contact member, and resilient means for backing up the outer ends of the individual wires whereby each individual wire may exert a greater yielding contact pressure than it could support from the mounting 30 end alone.

65. In a switch a relatively rigid contact member, and a relatively yielding multiple contact member, said multiple contact member comprising a rigid metal base, a plurality of flexible wires having mounting ends rigidly fastened into the base for mechanical anchorage and for the conduction of current thereto, said first contact member being movable endwise along the length 40 of the wires to slidably engage a lateral surface of the same, said wires having portions adjacent their outer ends bent to provide limited engagement of each wire with the cooperating surface of the relatively rigid contact member, said wires 45 providing multiple limited area high pressure contact engagement with said rigid contact member, and resilient means for backing up the outer ends of the individual wires whereby each individual wire may exert a greater yielding contact pressure than it could support from the mounting 50 end alone, and motion limiting means rigid with the base for limiting the deflection of said wires 55 individually within their elastic limits, said motion limiting means having lost motion connection with said individual wires to permit free motion 60 within limits of the individual wires.

ALLAN RAMSEY. 65
